UNITED STATES PATENT OFFICE

JOHN MELOTT, OF LOS ANGELES, CALIFORNIA

BLOW-OUT PREVENTER

Application filed September 7, 1927. Serial No. 218,023.

My invention is a blow out preventer for oil well work to prevent a blow out when drilling, or in other similar operations.

An object of my invention is a blow out 5 preventer having a plurality of slips slideable upwardly and inwardly so that if a blow out occurs in a well, these slips may be controlled to give the initial lift into position, and the greater the pressure of the gas in the 10 well, the tighter the closure made by the blow out preventer; thereby using the pressure in the well as the main element in sealing off the well.

Another object of my invention is in a blow 15 out preventer using a plurality of outwardly and inwardly moving slips having rubber or the like packing to engage between a stationary seat and a drill pipe to provide a simple manually controlled mechanism for 20 releasing the slips from the normal inactive lower position, and giving these an initial upward and inward movement in the proper position to be actuated by the pressure of the gas in the well, and forming a tight seal 25 between the seat and the drill pipe.

Another object of my invention is the construction of blow out preventer having a plurality of upwardly and inwardly movable slips, such slips being arranged whereby the 30 slushing mud used in slushing the well will not interfere with the operation of the slips.

In constructing my invention I apply a suitable head to the top of a well casing and on this head I mount a seat for the blow out 35 preventer, this seat being of substantial construction and having an outwardly and downwardly diverging inner wall, such wall being substantially a frustum of a cone with the apex upwardly. Slips of the proper shape 40 to engage the seat are mounted in the structure between the well casing cap and the seat mounted thereon. These slips have a vertical surface forming part of the cylinder, and an outwardly coned surface, a flat base, and usually a short cylindrical outside wall. The 45 slips are covered on the conical face and on the inner cylindrical face with rubber packing, or the like, to engage, respectively, the seat and a drill pipe, or other equipment.

50 In one form of my invention the slips are

counterweighted by a heavyweight with cables connected to the top of the slips. These cables pass over a suitable pulley system so that one weight functions to lift all of the slips into their closing position. In 55 another arrangement, the slips rest on a flat metal ring and this ring is thrust upwardly by a plurality of thrust rods, such rods being elevated by means of a heavy counter-weight with flexible cables.

In each of these constructions I use a manually operated latch which in one position holds the slips in their normal inoperative position, that is, in their lowermost location, and on release, allows the counter-weight to 60 elevate the slips. In another construction I have the thrust rods which lift the slips actuated by a hydraulic, compressed air or steam cylinder piston system, such being manually controlled so that the slips may be 65 quickly forced upwardly on indications that the well is about to blow.

70 My invention will be more readily understood from the following description and drawings, in which:

75 Figure 1 is a plan view of my invention taken substantially on the line 1—1 of Fig. 2 in the direction of the arrows.

Figure 2 is a vertical section taken substantially on the line 2—2 of Fig. 1 in the 80 direction of the arrows, showing a derrick floor with a turn-table thereon.

Figure 3 is a section somewhat similar to Fig. 2 of a modification in which thrust rods are used to elevate the slips connected to 85 counter-weights.

Figure 4 is a detail section on the line 4—4 of Fig. 3 showing the interconnection of the thrust ring and the slips.

Figure 5 is a section somewhat similar to Fig. 3 of a further modification showing the thrust rods, thrust ring and slips being elevated by a fluid operated system.

Figure 6 is a horizontal cross-section on the line 6—6 of Fig. 5 in the direction of the 95 arrows.

Figure 7 is a horizontal section on the line 7—7 of Fig. 2 in the direction of the arrows showing the toggle connection for forcing uniform action of the slips.

Figure 8 is an irregular vertical detail on the line 8—8 of Fig. 7 in the direction of the arrows.

In the construction shown in Fig. 1 and Fig. 2 a well casing is indicated by the numeral 11, having a substantial cap 12, this cap having a horizontal flange 13. Slushing outlet pipes 14 are connected to the cap and have control valves 15. Rotary drill tubes 16 are illustrated as being used in the well, and on the floor 17 there is a rotary rig or turn-table 18 which is of the usual character. My invention is intended to engage a drill pipe, or the like, and prevent a blow out of the well, should the well begin to gas.

In my invention I mount a heavy housing 19 which is bolted to the flange 13 of the well cap. This housing preferably has a cylindrical large bore 20, an upwardly and inwardly inclined seat 21, and upper vertical slots 22. There are also a plurality of guide pins 23 which are secured to the flange 13 and extend upwardly and inwardly on an inclination parallel to the seat 21.

A plurality of slips 24, of which four are shown, are fitted in the housing. These slips have a flat base 25, an outer wall 26 concentric to the wall 20, an inner surface 27 which is substantially on the same curvature as the circumference of the drill pipe 16. The upwardly and inwardly inclined surface 28 is parallel to the seat 21 and the slips also preferably have a flat top 29. Each of the slips has an internal packing 30 fitted in a recess 31, and an external packing 32. These packings are preferably of rubber. There are also holes 33 to accommodate the inclined pins 23.

A cable 34 is connected to each of the slips, the connection being by eyes 35, and each of these cables passes over a pulley 36 on the top of the housing, these pulleys extending inwardly of the small bore 22 and rotate in vertical planes. There are also a series of guide pulleys 37 mounted on studs 38 on top of the housing 19 and these operate on a horizontal plane. One of the cables 39 passes over a guide pulley 40. All of these cables lead to a set of drums mounted on the shaft 42 which has a hand wheel 42', the shaft being supported on brackets 43. One or more of the cables, after a few turns on the drums, has a vertical drop 44 with a counter-weight 45. The hand wheel 42' may be used to initially start the actuation of the slips or to give a binding tension on the cables when they are fully closed in.

The trip mechanism comprises a stop clamp 46 which is attached to the drop cable 44 and this clamp is engaged by a bifurcated cam 47 connected to the latch arm 48, this arm being mounted on a pivot pin 49 supported on the bracket 50. A hand line 51 connects to the latch. The bifurcated cam engages on both sides of the clamp 46.

The manner of operation of my invention

as shown in Figs. 1 and 2 is substantially as follows:

In the normal inoperative position of the slips, these rest as shown in Fig. 2 on the flange 13; the cam 47 engages the clamp 46 and supports substantially all the weight of the counterweight 45 so that the counterweight does not act on the slips, tending to pull these upwardly. In this condition the drilling operation may be carried on. For instance, a rotary drill pipe may be used in the well, there being sufficient clearance for the couplings, the various drilling tools and the like. Should the well begin to blow, the operator pulls the hand line 51 which, drawing down on the latch arm 48, rocks the bifurcated cam 47 on its pivot 49, thereby releasing the cam from the clamp 46, which allows the full weight of the counterweight 45 to act on the slips. As this counterweight is materially greater than the weight of the slips, the slips are pulled upwardly and inwardly, the inclined seat 21 forcing them inwardly so that the rubber packing 30 engages the side of a drill pipe and the packing 32 on the upper surface wedges against the seat, thus giving a gas and liquid tight joint and preventing blowing out of the well.

When it is desired to lower the slips again, the counterweight is elevated in any suitable manner, and the bifurcated cam fitted underneath the clamp, and in this procedure the slips are guided into their position shown in Fig. 2 by the inclined pins 23.

My blow out preventer as illustrated in Figs. 3 and 4 is constructed substantially as follows:

In this case the well casing cap 12 is provided with a flange 60 with a series of openings 61 therethrough with stuffing boxes 62. The housing 19 and the slips are substantially the same as illustrated in connection with Figs. 1 and 2. These slips rest on a ring 63 having a plurality of radial slots 64, there being one slot for each slip. The guide pins 23 secured to the flange of the casing cap pass upwardly through the slot 64 engaging in the slips. Thrust rods 65 extend upwardly through the packings 62 and engage the lower surface of the ring 63. The lower ends of the thrust rods 65 bear on a sliding collar 65', this collar having the cables 66 secured thereto, all of which pass upwardly over guide pulleys 67 operating in vertical planes. Some of these cables extend over horizontal guide pulleys 68, these pulleys being mounted on brackets 69 and 70 secured to the flange of the casing cap. All of the cables lead over drums 71 on a horizontal shaft 71' having a hand wheel 71" on the shaft. The shaft is journaled in brackets 72. One or more of the cables after a turn on the drums is connected to a counter-weight 73. The drop line 73' of the cable has a clamp construction similar to that used in connection with Figs. 1 and 2.

In the operation of the device of Figs. 3 and 4 when the slips are in their normal inoperative position, the ring 63 rests on top of the flange of the casing cap, the major portion of the weight of the counterweight being supported by the cam-shaped latch, which, should the well begin to blow, may be released and the counterweight will then act on the cables, lifting the collar and thrust rods, thus forcing the ring 63 and the slips into the upward position shown in Fig. 3, thereby gripping the drill pipe or the like.

The construction of my invention as illustrated in Figs. 5 and 6 is substantially as follows:

In this arrangement the casings, the slips and the thrust rod arrangement 65 for raising the slips are substantially the same as shown in Figs. 3 and 4. However, on the lower part of the well casing cap I have a plurality of cylinders 80. These cylinders have removable plugs 81 at the base and have suitable packing 82 through which extend the thrust rods 83, such rods being connected to pistons 84 and being equivalent to piston rods, such rods extending upwardly into the housing and engaging the ring underneath the slips.

The upper and lower ends of the cylinders are connected with pipes 85 and 86 which are joined by a pipe 87 having a suitable three-way valve being connected to a source of supply 89, and the other to a discharge 90. It is to be understood that all of the cylinders are connected to the same valve so that the manipulation thereof operates all the slips in unison.

The manner of operation and functioning of the arrangement shown in Figs. 5 and 6 is substantially as follows:

The slips are normally resting in their lower position in the housing and disengaged from the drill pipe or the like. In this condition the pistons would occupy their lowermost position in the cylinders. When it is desired to raise the slips, the valve is operated, forcing either hydraulic fluid, steam or compressed air, or an equivalent power medium, into the cylinders below the pistons, thereby elevating the pistons. This causes the upward thrust of the thrust rods and lifts the slips into engagement with the drill pipe, thus effectively sealing the well and preventing a blow out.

Should the slips be jammed tight to the pipe, especially by the internal pressure in the well, and it is desired to lower the slips, after releasing such pressure the valve may be operated in the opposite direction, forcing the power fluid into the upper part of the cylinders and depressing the pistons, the power medium being forced out of the lower part of the cylinders.

It will be noted in connection with Figs. 3 and 5 that the housing does not require any

upper slots, as indicated by the numeral 22 in Fig. 2. These upper slots may be eliminated from the construction of Fig. 2, provided the connection between the slips and the cable allows the slips to be drawn upwardly and forced inwardly sufficiently to engage a drill pipe. Also, if desired, the conical seat in the housing may extend downwardly substantially to the flange of the well casing cap, the slips being made to correspond with the internal shape of the housing.

From the above description it will be seen that I have developed several simple forms of a blow out preventer using slips which may readily be lifted into position to engage a suitable seat on a substantial housing, and to this end I may use either the force of gravity, as by a counterweight, or a positive impelling medium, such as steam, hydraulic or compressed air; also that the internal pressure of the well acts to cause a tighter seal, therefore, the greater the pressure in the well the tighter the well is sealed off. Also, by my construction, the slips may be readily returned to their original position after the pressure in the well has eased off.

In order to force the slips to act in unison, I may employ a toggle construction in each of the arrangements shown and given in detail in Figs. 7 and 8. Each of the slips is provided on its under surface with vertical recesses 95 extending inwardly from the side edges 96 of the slips. Toggle arms 97 are secured to pivot pins 98 or fitted in these recesses, and the free ends of these links are connected by a pivot pin 99. These toggles occupy the position shown in full lines in Fig. 7 when the slips are spread apart the full distance.

When the slips are drawn together, even if the drill pipe is out of center, the action of one slip in moving causes an action of the toggles, thereby forcing all the slips to act in unison so that there is no danger of one slip jamming, either due to the seating arrangement for the slips or to internal pressure in the well, because all the slips in being forced inwardly are also caused to act in unison; hence firmly abutting together and giving a positive seal to the drill pipe.

An advantage of having the positive control of the slips by the hand wheels on the shafts having the drums over which the cables are turned is that it insures a positive action of the slips, should, for any reason, the gravity-actuated control stick, as the hand wheels may be turned to give this an initial start and also if the slips are not sufficiently closed, to prevent blowing of the well the hand wheels may be turned to give the slips an upward and inward jam, thereby securing a tight seal.

It will be noted that the lower end of the slips, as shown in Figs. 3 and 5, are out-

wardly and upwardly tapered so that when the ring 63 lifts the slips, these have a tendency to slide inwardly over the inner edge of these rings.

5 Another feature forming a tight seal with my blow-out preventer occurs if a tool joint or collar comes into engagement with the lower surface of the slips, which action causes an upward wedging of the slips, effecting a tight seal above such tool joint or collar.

10 Various changes may be made in the principles of my invention without departing from the spirit thereof, as set forth in the description, drawings and claims.

15 I claim:

1. A blow out preventer comprising in combination a well casing cap having a flange, a housing connected thereto having a conical internal seat with the apex upwardly and having a large bore below the seat and a smaller bore above the seat, a plurality of slips each having a flat base, an outer surface conforming substantially to a large bore, an inner surface conforming to a drill pipe, and upper inclined surfaces conforming to the said seat, the slips in their inoperative position resting on their base on the flange with their inner surfaces spaced from a drill pipe, and means to elevate said slips, the seat engaging the inclined surfaces and forcing the slips inwardly with their inner surfaces engaging a drill pipe, and pins forming a guide means mounted in the housing and engaging holes in the slips to return the slips to their normal inoperative position, guiding said slips outwardly in their downward movement.

2. A blow out preventer comprising in combination a well casing having a horizontal flange, a housing connected thereto having an inner inclined seat with the apex upwardly, a large bore below the seat, inclined guide pins secured to the flange of the cap, a plurality of slips each having guide holes to engage the said pins, the slips having a base surface to conform to the flange and having an upper surface to conform to the seat and an inner surface to conform to a drill pipe, the surface of the slips engaging the seat having a resilient packing, the inner surface to engage the drill pipe having a resilient packing, said slips in their inoperative position resting on the flange and spaced from a drill pipe, and means to elevate said slips, the seat of the housing forcing the slips inwardly into engagement with a drill pipe, said slips being adapted for maintenance in said position by an internal pressure in the well casing.

3. A blow out preventer, as claimed in claim 2, the means to elevate the slips comprising flexible cables with a counterweight, and means interengaging the slips and the cables with a latch engaging one of the cables when the slips are in their inoperative position.

4. A blow out preventer comprising in com-

bination a well casing cap having a horizontal flange with openings therethrough and stuffing boxes therein with thrust rods slideable upwardly through said openings and the stuffing boxes, a housing mounted on the flange having an internal conical seat with the apex upwardly, a plurality of slips mounted in said housing, each slip having an upper inclined surface to conform to the seat and an inner vertical surface to engage a drill pipe, means interengaging the thrust rods and the slips, said slips in their inoperative position being spaced from a drill pipe, and means to actuate said rods to elevate same and thrust upwardly on the slips, the said seat of the housing forcing the slips inwardly into engagement with a drill pipe, the means to elevate the thrust rods comprising a cable connected to each rod, a counterweight connected to said cables, and a latch means interengaging with the cable and the counterweight when the slips are in their lower inoperative position.

5 In testimony whereof I have signed my name to this specification.

JOHN MELOTT.
